(57) **CLAIM**

The ornamental design for an electronic reader device, as
shown and described.

DESCRIPTION

FIG. 1 is a perspective view of the electronic reader device;
FIG. 2 is a front elevation view of the electronic reader device
of FIG. 1;

FIG. 3 is a back elevation view of the electronic reader device
of FIG. 1;

FIG. 4 is a bottom plan view of the electronic reader device of
FIG. 1;

FIG. 5 is a top plan view of the electronic reader device of
FIG. 1;

FIG. 6 is a left side elevation view of the electronic reader
device of FIG. 1; and,

FIG. 7 is a right side elevation view of the electronic reader
device of FIG. 1.

The broken lines are directed to environment and are for
illustrative purposes only. The broken lines form no part of the
claimed design.
